FIRE APPARATUS

Filed July 16, 1925

Inventor
Jacob B. Blow.

By Attorney.

UNITED STATES PATENT OFFICE.

JACOB B. BLAW, OF ATLANTIC CITY, NEW JERSEY; SADIE H. BLAW EXECUTRIX OF
SAID JACOB B. BLAW, DECEASED.

FIRE APPARATUS.

Application filed July 16, 1925. Serial No. 43,921.

The object of my invention is to provide a suitable means for supporting and adjusting a hose line and nozzle, and more particularly, for being supported from a ladder whereby 5 the hose nozzle may be quickly adjusted to any height of the ladder when in position against a wall and for directing the stream into the building against which the ladder is leaning or directing it across the street or in 10 the direction of a fire outside of the building.

My object is further to provide the adjustable nozzle support above referred to with means for quickly attaching and disconnecting it with respect to the rungs of a ladder 15 and provide portability when disconnected; and which devices shall also be capable of adjustability to a socket post on the hose truck or other vehicle to permit of its use thereon as well as its transfer from the fire hose 20 to the place of conflagration.

With the above and other objects in view, the nature of which will be more fully understood from the description hereinafter, the invention consists in the novel construction 25 of fire apparatus as hereinafter more fully described and defined in the claims.

Referring to the drawing: Fig. 1 is a vertical section showing my improved fire apparatus in position against the wall of a 30 building; Fig. 2 is a side elevation of my improved portable adjustable support and clamp for the hose and nozzle; Fig. 3 is a front elevation of the adjustable nozzle clamp separated from its socket support; Fig. 4 is 35 a plan view of the socket support with the nozzle clamp removed; and Fig. 5 is an elevation illustrating my improved portable device supported by a hose truck.

Referring more particularly to Fig. 1, 2 40 represents the front of a building and 3 a window therein. 4 illustrates the upper portion of a ladder leaning against the building at a point above the window and 5 are the rungs thereon. Suspended on one of the 45 rungs is the socket support 6, the lower end of which is strapped or suitably fastened to another and lower rung whereby the socket support is suspended in an upright position. To the upper end of the socket support is secured the hose and nozzle clamp shown, more 50 particularly, in Figs. 2 and 3. 28 represents the fire hose, the upper end of which is clamped in the hose and nozzle clamp and 29 is

the fire nozzle which, in the case of Fig. 1, is directed to guide the water stream through 55 the window into the interior of the building.

Referring more particularly to the construction of the portable device, comprising the socket support and hose and nozzle clamp as illustrated in Figs. 2, 3 and 4, attention 60 is directed more especially to the following features of construction: 6 is a tubular socket support and is provided at its upper end with a socket having its walls split, as at 7, to provide spring jaws, the same being surrounded 65 by a clamping collar 9 secured to the socket by a screw 9^a and having its two free ends 9^b relatively adjustable to or from each other under the action of a screw clamp 10 provided with a hand wheel 11 for conveniently 70 rotating it (Figs. 2 and 4). By this mechanism, the rotation of the hand wheel 11 clockwise will cause the collar 9 to contract about the spring ends of the socket to reduce the 75 internal diameter for the purpose of clamping and holding the shank 8 of the adjustable hose and nozzle clamp. Immediately below the socket clamp, I provide a rung clamp 12 which comprises a body part 13 fitting snugly 80 to the tubular socket 6 and secured thereby by transverse plates 16 and provided further with a hinged jaw 14 and a clamping screw bolt and nut 15, the same being hinged to the body part 13 and adapted to swing over into 85 clamping relation with the hinged jaw. This rung clamp is preferably provided so that it opens downwardly to permit easy disconnection for other adjustment, since the loosening of the wing nut will permit the screw bolt to swing down automatically to release the jaw. 90 The lower end of the tubular support 6 is provided with a transverse slot 17 desirably of considerable length, and is provided with a strap 18 which extends through the slot and is provided with a suitable buckle or fastening 95 device, the width of the strap being preferably much less than the length of the slot. When this socket support is adjusted to the rungs of the ladder, the parts take the position as indicated in Fig. 1, from which it will 100 be seen that the clamp 12 is fastened about one of the rungs 5 and the lower end of the tubular socket 6 is bound tightly to the next rung below by means of the strap 18. It is preferable that the tubular socket support 6 shall 105 extend between the rungs passing over one

of them and under the other, the purpose of which will be hereinafter described.

19 is a yoke shaped casting having at its lower part a shank 8 which is adapted to be received in the upper end of the tubular socket and clamped in adjusted positions therein, as before explained. The two upwardly extending arms of the yoke provide a space in which the nozzle clamp body 21 is received, said body being pivoted at 22 to the upper ends of the yoke arms and about which pivots the clamp body 21 may be oscillated for adjustment. The lower part of the body is provided with a segment 23 in arc form whose center is the axis through the pivots 22 and said segment is guided through a slot in the yoke 19 and is clamped therein by a manually operable screw clamp 24. In this manner, the body 21 may be adjusted to various angles in a vertical plane and rigidly positioned in such angular adjustment.

25 is a semi-circular clamping jaw being hinged at one end to one side of the body 21 and detachably clamped at the other end to the opposite side of the body by means of the hinged bolt and wing nut device 26, the screw bolt of which is hinged to the body and fits into a slotted flange portion on the semi-circular clamp 25. The body 21 constitutes a grooved saddle whose curvature approximates one-half of a circle, the other half of which is formed by the semi-circular clamping jaw 25 and is of a diameter approximately right for clamping the hose, as shown in Fig. 1, or a fire nozzle itself, as the case may be. The body or saddle portion 21 is provided with slots 21^a in the lower portion of its sides through which straps 27 are passed for strapping the hose or nozzle tightly in position so that it moves with the saddle for all adjustments thereof.

It will now be understood that when the tubular support 6 is positioned upon the rungs of the ladder, as shown in Fig. 1, and the hose and nozzle clamped to the adjustable saddle, the latter may be positioned by horizontal adjustment as well as adjustment in a vertical plane to direct the water stream in any direction desired. The adjustment in a vertical plane may be maintained by the clamping screw 24, whereas the adjustment in a horizontal plane may be maintained by the clamping socket formed by the part 7 and by the operation of the collar 9 and clamping screw 10.

In respect to the arrangement of the tubular support 6 under one rung and over the next rung, as shown in Fig. 1, it is pointed out that when the stream of water is on and especially where high pressure is used, the reaction is such that it would tend to force the yoke and its support backward and consequently, if the tubular support is arranged at its upper end under the rung, it is directly resisted against a backward movement.

However, as the connection with the rung by the clamp 12 acts as a hinge, it is necessary to hold the lower part of the tubular support 6 against movement in the opposite direction and for that reason the lower part of the tubular support is placed over and in front of the next lower rung and fastened to it by the strap 18. In this way, both of the rungs directly receive the thrust of the tubular support and obviate the necessity of depending upon the strap or upon the clamping jaw 14 for resisting the thrust due to the back thrust of the nozzle.

If, instead of the water stream being required to pass in at the window 3, it was required that it shall be projected upon a building across the street facing the building 2, then and in that event, the socket clamp 7 may be loosened and the nozzle turned in the reverse direction. Ordinarily, however, the tubular support with its nozzle clamp would be reversed to fit the two rungs of the ladder with the upper part extending in front of the upper rung and the lower part back of the lower rung, and the hose would be arranged so as to swing under the ladder instead of in front of it, as shown. This adjustment would be substantially equivalent to turning the ladder over so that the nozzle points in the opposite direction to that shown in Fig. 1.

It will be understood that the adjustable tubular support and the hose and nozzle clamp attached thereto is relatively light and easily portable, and would be shifted for adjustment to any portion of the ladder which was found convenient for the duty to be performed.

In Fig. 5, I have indicated at 30 a hose truck which may be of any suitable construction. The truck is provided with an upright socket 31 which has a tubular aperture somewhat larger than the outside diameter of the tubular support 6, and furthermore, is provided with a clamping means 32, said parts being utilized, if necessary, to sustain the tubular support in upright position if it is desired to utilize the truck by throwing a stream at some place where a ladder is not convenient or cannot be used. In this case, the strap 18 would be removed and the tubular support 6 would be inserted and clamped rigidly to the fixed tubular socket 31. If desired, one of these devices may be permanently associated with the hose truck or other vehicle.

While I have referred to the part 6 as a tubular support, this has been because ordinarily this part of the apparatus would be formed from a length of tubing, but I do not limit myself to the support being tubular throughout, as it would be sufficient that the socket end was made tubular and the rest of the structure made solid. However, as this would require either a small rod of equal weight to that of the tube or of a large solid

rod of an objectionable heavy weight, it is preferable that the support be made of a tubular structure throughout to secure strength and lightness.

5 It is also to be understood that while I prefer the elongated support to have a socket at its upper end to receive the shank of the hose and nozzle support with clamping means upon the elongated support for clamping the shank in the socket, I do not restrict myself to this arrangement as the parts may be reversed or otherwise formed at the option of the constructor without changing the spirit of the invention.

15 It will now be apparent that I have devised a novel and useful construction which embodies the features of advantage enumerated as desirable, and while I have in the present instance shown and described the preferred 20 embodiment thereof which has been found in practice to give satisfactory and reliable results, it is to be understood that I do not restrict myself to the details, as the same are susceptible of modification in various particulars without departing from the spirit or 25 scope of the invention.

Having thus described my invention, what I claim and desire to secure by Letters Patent is:

30 1. In a fire apparatus, an adjustable hose and nozzle clamp adapted for use with a ladder, consisting of an elongated unitary support having a socket in its upper end, clamping means at the upper part of the support 35 below and near said socket for direct attachment to one rung of the ladder, and separate adjustable means at the lower part of the unitary part and distant from the socket and clamping means for fastening the unitary 40 support to a lower rung of the ladder, a yoke having a shank adjustably fitting into the 45 socket end of the support whereby it is supported close to the clamping means, means for clamping the yoke in various positions of adjustment in the socket of the body, and a clamp for the hose and nozzle adjustably hinged to the yoke and having means for holding it in adjusted positions upon the yoke.

50 2. The invention according to claim 1, wherein the means for fastening the lower end of the support to the lower rung consists of an elongated transverse slot through the lower part of the support, and a strap and 55 buckle extending through the slot and of a

width less than the length of the slot so that it may be adjusted vertically to different positions.

3. The invention according to claim 1, wherein the means for clamping the yoke shank in the upper or socket end of the support consists of a tubular socket formed on the support and split longitudinally and having about it a spring collar having free ends, and a clamping screw extending through the free ends of the collar for drawing them together to provide a clamping action upon the split portion of the socket.

4. A fire apparatus, which consists of an elongated support having at its upper end a 70 socket provided with clamping means and also having near said socket and at one side of the elongated support an adjustable clamp comprising a body part and a hinged clamping jaw pivoted thereto with means for locking the jaw in closed relation and having at its lower end a transverse slot and strap extending therethrough and provided with a buckle, combined with a universally adjustable clamping means for the hose and nozzle 75 provided with a shank at its lower part adapted to fit into the clamping socket at the upper end of the elongated support.

5. In a fire apparatus, an adjustable hose and nozzle clamp adapted for use with a ladder, consisting of an elongated unitary support having a socket in its upper end, clamping means near said end for direct attachment to one rung of the ladder, and adjustable means at its lower part for fastening the 90 same to a lower rung of the ladder, a yoke having a shank adjustably fitting into the socket end of the body whereby it is supported close to the clamping means, means for clamping the yoke in various positions of adjustment in the socket of the body, and a 95 clamp for the hose and nozzle adjustably hinged to the yoke and having means for holding it in adjusted positions upon the yoke, and wherein the means for fastening the lower end of the support to the lower rung consists of an elongated transverse slot through the lower part of the support, and a strap and buckle extending through the slot and of a width less than the length of the slot 100 so that it may be adjusted vertically to different positions.

In testimony of which invention, I hereunto set my hand.

JACOB B. BLAW.
